THERMIONIC TUBE

Piet Marinus Cupido, Bernardus Octavianus Maria Gall, Johan Lodewijk Hendrik Jonker, and Adrianus Johannes Wilhelmus Marie van Overbeek, Eindhoven, Netherlands, assignors to Hartford National Bank and Trust Company, Hartford, Conn., as trustee

Application July 20, 1946, Serial No. 685,158
In Belgium May 1, 1945

Section 1, Public Law 690, August 8, 1946
Patent expires May 1, 1965

15 Claims. (Cl. 250—27.5)

1

In the use of thermionic tubes it is generally of great importance that each tube can be replaced by a tube of the same type without any need for modification of the apparatus in which the tubes are used. By the latest methods thermionic tubes may be manufactured in such a manner that substantially all the important characteristic magnitudes of several tubes of one type are equal within very narrow limits. It has been found, however, that as regards the capacities between the electrodes and with respect to the surrounding parts of the apparatus the permissible tolerances are so small that mass production of tubes which are interchangeable without further expedients is in practice impossible without involving excessively high manufacturing cost. This applies particularly to tubes intended for short waves.

It has been previously suggested that thermionic tubes should be provided with so-called trimmer electrodes or trimmer condensers in order to perfectly equalize the capacities in tubes of a given type. In one known method before the trimming operation is effected, the supply conductors of two electrodes are connected to coatings applied to the closing plate of the tube; by a mechanical operation, for example scratching off the coatings, their capacities are given the desired value with respect to one another. This operation requires great skill, which naturally results in an appreciable increase of the cost of the tube.

A thermionic tube according to the invention comprises a screening means and contains a trimmer condenser located in a space bounded in part by the wall of the bulb and in part by the screening means.

Wherever in the foregoing and hereinafter reference is made to the screening means of the tube, we mean thereby either an electrically conductive envelope which may be firmly applied to the wall of the tube, for example by the spraying process, or a conductive sleeve which is so slipped on the tube as to be clamped thereto. We mean thereby, in addition, a coating which may be applied, if desired, to the bottom of the tube through which the supply conductors for the electrodes are led in an insulating manner. For discharge tubes having a flat bottom the last-mentioned part of the screening means takes the shape of a dish provided with apertures for the passage of the supply conductors. In each case the screening means constitutes an integral part of the tube. It need not, however,

cover the whole of the wall of the tube but may extend over a portion thereof.

A thermionic tube according to the invention permits of obtaining appreciable advantages with respect to the above-described tube of known type. By placing the trimmer condenser in the space described, the capacity of the condenser on trimming the latter is not affected by the hand of the person carrying out the trimming operation. Furthermore, an important advantage is that the trimmer may be arranged in a dust-proof manner and is safeguarded against mechanical damage. The tube once trimmed thus always retains the same constants during its use. Furthermore, the screen prevents the trimming from being affected by fields located outside the tube, which is of special importance when the tube is inserted into the holder, since every holder has some influence on the capacities of the contact members and hence on the capacities of the electrodes. In the tube according to the invention the influence of the tube holder on the capacities is suppressed completely.

25 In the above-described known tube with trimmer electrodes which are constituted by a conductive coating on the bottom of the tube, it is not possible to provide afterwards a screening means at the bottom of the tube, since such a screening means would result in a strong variation of the capacity already adjusted.

30 Numerous forms of construction of a trimmer condenser which may be used in a thermionic tube according to the invention are possible. The size of the condenser is of great importance since the dimensions of the tube are preferably kept down as much as possible. Since only the trimming of very low capacities is concerned, very small condensers are sufficient indeed, 35 which consequently may be easily arranged between the screening means and the bulb.

35 In one particularly advantageous form of construction of a thermionic tube according to the invention one electrode of the trimmer condenser is connected to the screening means. As a particular case thereof we must see a construction in which part of the screening means itself serves as one of the electrodes of the condenser. This form of construction is, as a rule, not serviceable for ultra-short waves, since in this case it is desirable that one of the electrodes of the trimmer condenser should be connected directly to the cathode.

50 In another form of construction one of the electrodes of the trimmer is constituted by part

of the supply conductor of the electrode whose capacity is to be adjusted. This construction is very simple since in this case only one additional electrode for the condenser need be provided.

In a further form of construction of the thermionic tube according to the invention the tube comprises a so-called flat bottom, by which we mean a closing member which is more or less plate-shaped. It need not be mathematically plane, however, but may exhibit some grooves, rims or protrusions. If this tube is provided at the bottom with a screening means, the trimmer is preferably placed between the screening means and the bottom of the tube. If one side of the trimmer is connected to the screening means, use may be made with great advantage of that construction in which a part of the screening means constitutes one of the electrodes of the condenser.

The movable part of the trimmer may be connected either to the supply conductor whose capacity is to be regulated, or to the other electrode with which the condenser is connected, for example the screening means. The latter form of construction affords the advantage that the movable part has a fixed potential and, consequently, the trimming is not affected by the use of a tool, for example a screw driver, for the adjustment of the trimmer.

In a highly advantageous form of construction of a tube according to the invention the movable part of the trimmer is constituted by the dielectric. This means that between the conductive electrodes of the trimmer there is provided a fixed dielectric which may be brought more or less between the plates, the dielectric in this case consisting partly of air and partly of the fixed insulating material.

In a particular form of construction one electrode of the trimmer is constituted by a conductive rod or strip connected to the supply conductor of the electrode to be trimmed. As an alternative, one of the electrodes of the trimmer may be applied to the insulating wall of the tube round the supply conductor of an electrode and an electric contact with the latter.

For fixing the movable part of the condenser against displacement subsequent to the trimming operation, use may be made of a cementing material; this manner of fixing is already known in itself.

The invention will now be explained more fully by several practical examples shown diagrammatically in Figures 1 to 13, inclusive, of the accompanying drawing. These figures show a portion of a tube closed by a plane bottom plate which is fixed to the bulb, for example, by fusion. In all the figures one of the electrodes is connected to the screening means. The invention is however by no means limited to tubes of this kind.

In Figure 1 the trimmer is a so-called tube trimmer.

In Figure 2 a portion of a supply conductor is also a part of the trimmer condenser. The same is the case in the forms of construction shown in Figures 3, 4 and 5.

In Figure 6 the trimmer is a wire trimmer, while Figures 7 up to 13 inclusive show trimmers constituted by two or more parallel plates.

In Figure 1, reference numeral 1 denotes the glass wall of the tube which is closed by the glass bottom 2, in which the supply conductors 3 of the system of electrodes, not shown, are fixed in a vacuum-tight manner. The bulb of the tube is

surrounded by a metal bushing 4, the bottom of which adjoins a metal dish 5 by which the tube is screened at the bottom. The supply conductors 3 are freely led through apertures 6 formed in dish 5. The supply conductor 3 is provided with a transverse rod 7 which is fixed to it at 8, for example, by spot-welding. Rod 7 is surrounded by an insulating sleeve 9 which is fixed on it. The insulating sleeve 9 is surrounded by a metal sleeve 10 which is slipped over sleeve 9 and connected at 11 to screening dish 5 by means of a flexible wire. The latter is freely passed through an aperture 12 so that sleeve 10 may be shifted around sleeve 9 likewise through the aperture 12 with the aid of a fine tool. Owing to the fact that a larger or smaller portion of sleeve 10 thus comes opposite the rod 7, the capacity of the electrode connected to the supply conductor is adjustable within certain limits.

In Figures 2 up to 13 inclusive identical parts of the thermionic tube are indicated by the same reference numerals.

Figure 2 shows a portion of a tube in which a trimmer condenser of very simple construction is provided between the glass closing plate and the dish-shaped screening means. The trimmer is constituted by a curved plate 13 which is secured to dish 5 at 14. A portion of supply conductor 3 serves as the counter-electrode for plate 13; through aperture 12 the latter may be bent more or less towards conductor 3 with the aid of a tool.

Figure 3 shows a portion of a tube in which a wire trimmer is used. This is constituted by a conductive wire 15 helically wound on an insulating sleeve 16. The latter surrounds supply conductor 3, a portion of which consequently serves as an electrode of the condenser. The free end of the wire 15 is led through aperture 12 and secured to the dish-like screening means at 11. When pulling the part of the wire 15 which is passed through the aperture, the sleeve 16 turns around supply conductor 3, due to which a portion of the wire is wound off and the capacity of the condenser decreases. The wire 15 may be fastened to sleeve 16 in known manner by means of a thin lacquer layer. To facilitate the turning motion round conductor 3, a second sleeve may be provided between the latter and sleeve 16.

In Figure 4 the trimmer is constituted by a flanged sleeve 17 arranged so as to be slidable around supply conductor 3. Between conductor 3 and sleeve 17 is an insulating material 18 which may consist of some plastic material or other which hardens by local heating or, for example, under the action of air. Sleeve 17 is connected to screening means 5 at 19. The second electrode of the trimmer is constituted by a conductive layer 20 applied round supply conductor 3 to the bottom 2 of the tube. The conductive layer 20 may consist, for example, of a stucked metal foil or a silver coating on the bottom 2 of the tube. It is applied so as to be in electrically conductive contact with supply conductors 3. By shifting sleeve 17 along supply conductor 3 with the aid of an instrument passed through aperture 21 of dish 5, the capacity of the trimmer is adjusted.

In Figure 5, part of supply conductor 3 constitutes one electrode and sleeve 22 constitutes the other electrode of the trimmer condenser. A plastic material 23 is provided between the two electrodes. Sleeve 22 is connected to the screening means 4 at 24. The trimmer is adjusted to the correct value by deformation of

sleeve 22, for which purpose the material 23 must be plastic. Consequently, use is preferably made of some material or other which hardens after being treated, for example a hardening cementing material. Since the deformation operation must be effected with the aid of a pair of tongs or a similar tool, this construction is not suitable for a tube utilising a dish-like screening means. In order nevertheless to obtain a screening means for the lead-through conductors, bushing 4 surrounding the bulb of the tube is caused to protrude downwards.

Figure 6 shows a form of construction in which use is made of a wire trimmer which surrounds, in contradistinction to the form of construction of Figure 3, a transverse rod 25 fixed to supply conductor 3. The wire is led to the exterior through an aperture 12 and secured to the screening means at 11. Since in this case the direction in which the wire is pulled during the trimming operation is the same as that of the electrode 25, the insulating sleeve must naturally be firmly fixed to the rod 25 or at least be locked against sliding off this rod.

In Figure 7 one electrode of the trimmer is constituted by a conductive plate 26 which is slipped upon supply conductor 3, and can slide along the latter. Part of the screening means 5 serves as the other electrode of the trimmer. By displacing a plate 26 the capacity thereof and hence of the electrode to be trimmed with respect to the screening means 5 may be adjusted. The shifting operation along conductor 3 may be effected, for example, with the aid of an instrument which is passed through aperture 27. An insulating plate 28 may be provided between plate 26 and the screening means 5. The dielectric of the condenser in this case partly consists of air and partly of an other insulating material. In this construction a satisfactory contact between conductor 3 and plate 26 must be ensured.

Figure 8 shows a modification of the construction of Figure 7, in which plate 26 is shifted by turning instead of by sliding. To this end conductor 3, together with the hole in plate 26 are threaded at 29.

Figure 9 shows a form of construction of a trimmer which does not substantially bring about any increase of the dimensions of the tube. One electrode of the trimmer is in this case constituted by a coating 30 on the bottom of the tube round supply conductor 3 and in electric contact with the latter. The other electrode of the condenser is constituted by a part of the screening means 5. An insulating plate 31, which can turn about conductor 3, is provided between the two electrodes. Owing to the particular shape of this plate and that of the conductive coating 30 it is possible by turning the plate to bring a larger or smaller part thereof between the condenser electrodes. Consequently, in this case the air dielectric is replaced by the insulating plate, due to which the capacity of the condenser is varied. Since plate 31 and coating 30 may be given any arbitrary shape, it is possible to obtain a definite manner of variation. This figure and Figure 10, which is a bottom view of the trimmer, show in addition in what manner plate 31 is accessible through an aperture 32 provided in the wall of the tube. This aperture is formed, for example, by milling away a small portion at the bottom of the screening means, as is shown in perspective in Figure 13. The particular advantage of the construction of Figures 9 and 10 firstly lies in the exceptionally small

dimensions and, in addition, in the fact that in this case an insulating part is turned. A satisfactory contact with the fixed electrode of the condenser is thus always ensured. In a particular form of construction of this condenser apertures of determined shape may still be formed in insulating plate 31.

Figure 11 shows a form of construction of a trimmer in a tube according to the invention in which the movable part, the rotor of the condenser, is constituted by a conductive plate 33 which is rotatably arranged around supply conductor 3 and in electric contact with it. An insulating disc 34 (Fig. 12) exhibiting an aperture 35 of any arbitrary shape is provided between plate 33 and the screening means, a portion of which serves as the second electrode of the condenser. As can be seen from the plan of the condenser in Figure 12, the conductive plate 33 approximately has the shape of a hemisphere. By turning this plate, which may be effected through aperture 12, opening 35 provided in plate 34 is covered more or less, due to which the capacity of the trimmer condenser varies. As before, in this construction a satisfactory contact between plate 33 and supply conductor 3 must be ensured. In one particular form of construction, which is not shown, the aperture may alternatively be formed in the screening means which serves as an electrode of the trimmer. Turning plate 33 over disc 34, which in this case need not have any aperture, has the effect of changing the total surface of the opposite electrodes of the condenser. From this ensues a variation in capacity.

The forms of construction of tubes according to the invention shown in Figures 1, 2, 4, 7, 8, 9, 10, 11, 12 and 13 afford more particularly the advantage that the movable part of the trimmer condenser is adjustable in two directions. Consequently, the exact position of the trimmer may be found very accurately by moving this part to and fro.

As a matter of fact, numerous forms of construction of trimmers in addition to those shown in the figures are possible.

What we claim is:

1. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having first and second electrodes and a dielectric therebetween, one of said electrodes being in direct electrical contact with said screening means.
2. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having first and second electrodes and a dielectric therebetween, one of said electrodes being in direct electrical contact with said screening means, the other of said electrodes being constituted by a portion of the said supply conductor.
3. A thermionic tube comprising a bulb por-

tion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall member, said trimmer condenser having a movable and a fixed electrode and a dielectric therebetween, said movable electrode being electrically connected to said supply conductor and said fixed electrode being constituted by said screening means.

4. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having first and second electrodes and a movable dielectric therebetween, one of said electrodes being in direct electrical contact with said screening means.

5. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having a movable and a fixed electrode and a dielectric therebetween, said movable electrode being in direct electrical contact with said screening means.

6. A thermionic tube comprising a bulb portion having a wall member, a supply conductor secured in said wall member of said bulb portion, a screening means mounted on said bulb portion and also having a wall member, said wall member of said bulb portion and said screening means forming a spacing, and a trimmer condenser positioned in said spacing formed by said wall members, said trimmer condenser having first and second electrodes and a dielectric therebetween, one of said electrodes being in direct electrical contact with said screening means, the other of said electrodes being constituted by an elongated conductive element in electrical connection with the said supply conductor.

7. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having first and second electrodes and a dielectric therebetween, one of said electrodes being in direct electrical contact with said screening means, the other of said electrodes being constituted by an electrically conductive coating positioned on said wall member of said bulb portion and surrounding said supply conductor and in electrical contact therewith.

8. A thermionic tube comprising a bulb portion having a wall member, a supply conductor secured in said wall member of said bulb portion, a screening means mounted on said bulb portion

and also having a wall member, said wall member of said bulb portion and said wall member of said screening means forming a spacing, and a trimmer condenser positioned in said spacing formed by said wall members, said trimmer condenser having a first electrode constituted by a transverse rod secured to said supply conductor, a second slidable electrode surrounding said first electrode and a dielectric therebetween extending coaxially of said first and second electrodes, the slidable electrode being in direct electrical contact with said screening means.

9. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having a first electrode constituted by a transverse rod secured to said supply conductor, a second helically wound conductor electrode and a dielectric therebetween and extending coaxially of said first and second electrodes, the said helically wound conductor electrode being in direct electrical contact with said screening means.

10. A thermionic tube comprising a bulb portion having a wall member, a supply conductor secured in said wall member of said bulb portion, a screening means mounted on said bulb portion and also having a wall member, said wall member of said bulb portion and said wall member of said screening means forming a spacing, and a trimmer condenser positioned in said spacing formed by said wall members, said trimmer condenser having a first electrode constituted by said supply conductor, a second helically wound conductor electrode and a dielectric therebetween, extending coaxially of said first and second electrodes, the said helically wound conductor electrode being in direct electrical contact with said screening means.

11. A thermionic tube as claimed in claim 1 wherein the first of the said electrodes of the said trimming condenser is in electrical contact with the said screening means and the said second electrode is constituted by an electrically conductive plate rotatable about the said supply conductor, the dielectric between these electrodes comprising an insulating plate having a shape such that rotation of the said second electrode varies the area relationships of said insulating plate and said second electrode.

12. A thermionic tube as claimed in claim 11 wherein the said insulating plate has an aperture therein whereby the portion of said aperture adjacent the rotatable electrode is varied by the said rotation thereof.

13. A thermionic tube as claimed in claim 1 wherein the first of the said electrodes of the said trimming condenser is constituted by the said screening means and the said second electrode is constituted by a conductive coating positioned on the wall member of said bulb portion surrounding the said supply conductor and in electrical contact therewith, the said dielectric comprising an insulating plate rotatable about the said supply conductor, such that said rotation varies the area relationship between said insulating plate and the said electrodes.

14. A thermionic tube as claimed in claim 1 wherein the first of the said electrodes of the

said trimming condenser is constituted by the said screening means having an aperture therein and the said second electrode is constituted by a conductive plate rotatable about the said supply conductor and in electrical contact therewith, the rotation of the said second electrode over the said aperture of the said first electrode being such that the area relationships of the said electrodes are varied.

15. A thermionic tube comprising an exhausted vessel composed of insulating material and having a flat bottom, supply conductors secured in said flat bottom, a screening means having an aperture therein and including a metal cup element secured to said vessel at said flat bottom, said bottom and said element forming a spacing, said supply conductors passing through said spacing and through the said element and in insulated relationship with said element, a trimmer condenser in said spacing and comprising a movable electrode, said electrode

being adjustable through said aperture in said screening means.
